per O. Ed Duff
Attorney.

UNITED STATES PATENT OFFICE.

SAMUEL E. HARSH, OF WABASH, INDIANA, ASSIGNOR OF ONE-HALF TO JOHN M. HARTER, OF SAME PLACE.

OVERDRAW CHECK-SPREADER.

SPECIFICATION forming part of Letters Patent No. 401,558, dated April 16, 1889.

Application filed June 1, 1888. Serial No. 275,769. (No model.)

To all whom it may concern:

Be it known that I, SAMUEL E. HARSH, of the city of Wabash, in the county of Wabash and State of Indiana, have invented certain 5 new and useful Improvements in Check Spreaders and Holders; and I do hereby declare that the following is a full, clear, and exact description of the invention, which will enable others skilled in the art to which it applies 10 to make and use the same, reference being had to the accompanying drawings, and to the letters of reference marked thereon, which form part of this specification.

My invention relates to an improvement in 15 checkrein-spreaders.

Heretofore checkrein-spreaders have been formed of a bar provided with loops to which the checkrein is secured, and its center having a swelled loop inclosing a vertical bar, 20 and the rearwardly-extending loop by which the device is secured to a check-hook consists of a strip of leather passed through the loop and around said bar, and secured by having its two parallel lengths sewed together at the 25 center, and single overdraw checkrein-holders (not spreaders) have been constructed of a quadrangular metal frame closed at its front side, forming a straight bar around which the checkrein is passed, but having its opposite 30 side bar split and open, and having rearwardly-extending check-pieces extending from the two free ends of said rear side bar, and provided with projections upon their inner faces, the flexible loop being formed of a 35 looped piece of leather having its ends placed between said check-pieces and notched to receive said projections, and the flexible loop is secured between the check-pieces by a screw passed through the same and the ends of the 40 leather; but these old devices possess many disadvantages and are different from my invention as hereinafter set forth.

The object of my invention is to provide an improved checkrein-spreader exceedingly 45 cheap in first cost, simple and durable in construction, and in which the joint or fastening between the rigid bar of the spreader and the flexible loop is so constructed and arranged that small pieces, scraps, or other odds and 50 ends of leather can be used to form the flexi-

ble loop, thereby greatly economizing material and reducing the expense of production, and also, and more especially, centrally and rigidly connecting the flexible loop and the rigid metallic bar of the spreader, so that 55 there will be no independent motion between the two, except that allowed by the elasticity of the leather.

With these ends in view my invention consists in the combination of a rigid metallic 60 bar provided with rigid loops formed integral with its opposite ends, and in the same plane, to which the checkrein is secured, a pair of parallel ears formed integral with said bar and extending rearwardly from the central 65 portion of the same between the rigid loops, the inner adjoining faces of said ears being smooth and located a distance apart, and the rear edge of the bar between the ears being squared to form a square shoulder at right 70 angles to the adjoining faces of the ears, the rearwardly-extending loop formed of a single piece of leather, the ends of which are squared and located between said ears with the squared ends bearing against the shoulder at 75 the center of the bar and a rivet passing through the ears and ends of the leather.

Referring to the accompanying drawings, Figure 1 is a perspective view of the checkrein spreader as in use, showing a checkrein- 80 hook and the checkrein attached to the same. Fig. 2 is a plan view of the parts composing the spreader detached and in position to be assembled.

In the drawings, the reference-letter A indicates the spreader, consisting of the integral rigid metallic body portion B and the rearwardly-extending flexible loop C.

The body B consists of a solid approximately straight metal bar b, provided at its 90 opposite ends with the closed loops c, integral with the bar, and to which the checkrein is secured. The loops c extend in the same plane, and the straps from each side of the animal's head are secured to the loop upon 95 their respective sides, and the checkrein is thus spread, the bar b being of such length that the loops upon the ends of the same will hold the straps of the checkrein the desired distance apart. A pair of corresponding par- 100

allel lugs or ears, d d' , are formed integral with the center of the bar b , and extend rearwardly from the rear edge of the same, with their smooth-faced inner adjoining faces located a distance apart. The rear edge of the bar b , between the inner faces of the ears, is squared to form a square shoulder, e , between the same, and said ears are provided with coinciding transverse apertures for the passage of one or more screws or rivets, f , or the like.

The flexible loop C is formed of a single piece of leather or other flexible material, the opposite ends of which are cut off square and inserted in the rectangular socket formed by the ears and shoulder so as to fit tightly, and the same are rigidly confined in said socket by the rivet f , extending through the same. It should be observed that the lugs and square shoulder upon which the squared ends of the leather bear form a rigid connection with the metallic bar and prevent movement or friction at the joint.

My invention is different from and possesses many advantages over the old devices before mentioned, the spreader mentioned merely consisting of a body having a loop inclosing a bar which is loosely surrounded by the flexible loop. It is evident that I do not claim such a construction, as the object of my device is to rigidly secure the flexible loop to the center of the rear edge of the rigid bar to prevent movement at the joint, all the movement that is required being allowed in my device by the flexibility of the leather and the looseness with which it fits the checkhook.

The overdraw checkrein-holder mentioned

shows a split quadrangular frame having the cheeks provided with projections and extending from the free ends; hence it would be impossible to use this old manner of fastening in a spreader, as the bar of my device must be continuous and solid. Thereby the strength and durability of the article are greatly increased and its appearance improved, and, further, in my construction it is not necessary to employ the projections and notched ends by reason of the square shoulder e ; hence it will be obvious that my improved article is different from any of these old devices, and that I in no way make any claim to them; but

What I do claim is—

A checkrein-spreader consisting, essentially, of a single continuous integral bar provided with rigid loops on its ends, and in the same plane a pair of parallel ears formed integral with said bar and extending rearwardly from the central portion of the rear edge of the bar, the inner faces of said ears being smooth and located a distance apart, and the edge of the bar between the same forming a square shoulder, the flexible loop composed of a single piece of flexible material having its ends squared and located between said ears and bearing against said shoulder, and a pin passing through the ears and said ends, substantially as set forth.

In testimony that I claim the foregoing as my own invention I affix my signature in presence of two witnesses.

SAMUEL E. HARSH.
